US00D619388S

(12) **United States Design Patent**
Mead et al.

(10) **Patent No.:** **US D619,388 S**
(45) **Date of Patent:** **** Jul. 13, 2010**

(54) **WORKSTATION**

(75) Inventors: **Karl J. Mead**, East Grand Rapids, MI (US); **Alan E. Rheault**, Grand Rapids, MI (US); **George K. Vangelatos**, Fair Oaks, CA (US)

(73) Assignee: **Steelcase Inc.**, Grand Rapids, MI (US)

(**) Term: **14 Years**

(21) Appl. No.: **29/335,628**

(22) Filed: **Apr. 17, 2009**

(51) **LOC (9) Cl.** **06-03**

(52) **U.S. Cl.** **D6/482**

(58) **Field of Classification Search** D6/480-489, D6/429-431, 511, 495, 496, 477; 108/150, 108/151, 152, 153.1, 157.1, 161, 64, 66; 248/188, 188.1, 188.8
